UNITED STATES PATENT OFFICE.

NICOLAUS AUGUST OTTO, OF COLOGNE, ASSIGNOR TO THE GAS MOTOREN FABRIK DEUTZ, OF DEUTZ-ON-THE-RHINE, GERMANY.

MOTOR-ENGINE WORKED BY COMBUSTIBLE GAS OR VAPOR AND AIR.

SPECIFICATION forming part of Letters Patent No. 390,091, dated September 25, 1888.

Application filed March 27, 1888. Serial No. 268,630. (No model.) Patented in England February 28, 1888, No. 3,020; in Belgium March 19, 1888, No. 81,098, and in Italy May 8, 1888, XLV, 406.

To all whom it may concern:

Be it known that I, NICOLAUS AUGUST OTTO, a citizen of Prussia, residing at Cologne, in the German Empire, engineer, have invented certain new and useful Improvements in Motor-Engines Worked by Combustible Gas or Vapor and Air, (for which I have obtained patent in Belgium, No. 81,098, dated March 19, 1888; in Italy, No. 496, Vol. XLV, dated May 8, 1888, and have made application for patent in Great Britain, No. 3,020, dated February 28, 1888,) of which the following is a specification.

This invention relates to that class of motor-engines worked by combustible gas or vapor and air, in which the engine operates with a cycle of four strokes—namely, drawing in the combustible charge, compressing the same, firing and working stroke, and expelling the products of combustion.

The present invention has for its object to obtain increased power and useful effect from such engines; and it consists in a novel combination of devices, whereby, first, there is admitted to the cylinder-charge at the end of the suction-stroke a charge of compressed-air or other non-combustible gas under a certain pressure, so as to increase the volume of the charge and give it an initial compression before the compressing-stroke; and, secondly, at the end of the working-stroke a portion of the combustion-gases is caused to pass into a reservoir in order to be further utilized by subsequently performing work in expanding. For effecting these objects the following construction of engine is by preference employed:

The engine-cylinder is closed at both ends, and communicates at the front end—that is, the end opposite that at which the combustible charge is admitted—with a reservoir, there being two communicating passages—one at the extreme end of the cylinder, and a second one that is uncovered by the piston as it completes its suction and working-outstrokes. Furthermore, there is provided at the front end of the cylinder a valve serving both for the inlet of air and the escape of combustion-gases to and from the front end of the cylinder. The back end of the cylinder being provided with the

usual chamber for the compressed charge, the valve for the admission of the combustible charge, the escape-valve for the products of combustion, and the igniting-slide worked by a counter-shaft moving at half the speed of the engine-shaft, the action of the engine will be as follows: Assuming that the reservoir is filled with air or other non-combustible gas under pressure, the piston on completing its suction-outstroke uncovers the communication between the reservoir and cylinder, so that a portion of the air under pressure will enter the latter, thus increasing the cylinder-charge and putting it under an initial pressure. The piston then performs its compressing-instroke for compressing the charge, and at the same time the air or gas still remaining under a certain pressure in the reservoir will expand into the front end of the cylinder, assisting in the work of the compressing-stroke until it has expanded down to atmospheric pressure, when the before-mentioned inlet and discharge valve will be opened, so as to allow atmospheric air to enter while the piston completes its compressing-stroke. On the compressed charge being now fired, causing the piston to perform its working-outstroke, the said valve may be either closed or open, so as either to cause the air in front of the piston to be compressed into the reservoir, or to allow it to escape into the atmosphere, in which latter case the valve is, however, closed before the piston uncovers the before-mentioned communication with the reservoir, so that when this takes place a portion of the combustion-gases will pass into and be stored up in the reservoir, in order when the piston performs its following instroke for expelling the combustion-gases from the cylinder in the usual manner to pass into the front end of the cylinder and in expanding to perform work. When the piston has completed its expelling-stroke, the valve to the front end of the cylinder is opened, so as to allow the combustion-gases under pressure still remaining in the front end of the cylinder to escape into the atmosphere, and on its being again closed the piston, in performing its suction-outstroke at the commencement of the next cycle, will

compress the gas and air in front of the piston into the reservoir through both the said passages. The engine is then in the condition first above described, and the cycle of operation, as set forth, is repeated.

5 The discharge and admission valve to the front end of the cylinder may be actuated by a sliding cam on the counter-shaft of the engine, which is controlled either by hand or by a 10 governor, so as, by opening or closing the valve sooner or later, to vary the degree of compression of the air and gases in the reservoir.

15 The accompanying drawings show diagram sections of the cylinder and reservoir of a gas-motor engine constructed according to the above-described invention.

Figure 1 shows a sectional plan, and Fig. 2 a cross-section.

20 The engine-cylinder *a* is closed at its front end and communicates, first, by two passages, *h* and *i*, with the reservoir *b*, and, secondly, by a passage with an inlet and outlet valve, *g*, actuated by cams *n* on the counter-shaft *o*, which revolves at half the speed of the engine-shaft. The stroke of the piston *c* extends to the dotted line, leaving the space *a'* in the back end of the cylinder for containing the compressed charge, which is admitted 25 through the valve *e* and ignited by the igniting-tube *m*, made to communicate with the cylinder at the proper moment by the slide worked from the counter-shaft in the known manner.

30 *f* is the discharge-valve for the combustion-gases, opened at the required moment by means of a cam, *r*, on the counter-shaft, also in the known manner.

It will be seen that piston *c* toward the end 40 of its suction and working outstrokes uncovers the passage *h*, leading to the reservoir, so that in the one case compressed air and combustion-gases previously stored in the reservoir will pass from the same into the combustible charge contained in the cylinder, while in the other case the products of combustion will expand from the cylinder into the reservoir. The passage *i*, on the other hand, always communicates with the front end of the cylinder, 45 so that during the compressing-instroke the air and gases under pressure remaining in the reservoir will expand into the cylinder, doing work first through passage *i* and then through both *i* and *h*, while during the expelling-instroke the products of combustion will expand 50 from the reservoir into the cylinder in the same manner.

The valve *g* opens toward the end of the compressing-instroke to admit the outer air, 60 and also during the working-outstroke for the escape of air and gases, while during the suction-outstroke and expelling-instroke the valve remains closed, it being opened momentarily at the end of the last-named stroke for the escape of the combustion-gases. The valve may 65 either be immediately closed again before the commencement of the suction-outstroke, so as

to effect the compression of the air and gases in front of the piston during the whole of such stroke, or it may be kept open during part of such stroke, so as to limit the degree of compression to any desired extent. For this purpose the cam *n*, actuating the valve *g*, is mounted 70 on a sleeve, *p*, that can be slid on the shaft *o*, so as to bring parts thereof with a longer or 75 shorter dwell opposite the valve-lever *l*, as may be required. Instead of arranging the passage *h* in this position shown, so that the opening and closing thereof are effected by the piston itself, it may be placed in other positions, such as at *h'*, in which case the opening and closing thereof at the proper times for 80 effecting the above-described operations would have to be effected by a cam on the counter-shaft *o* in a similar manner to the valves *f* and *g*.

Having thus described the nature of my invention and the best means I know for carrying the same into practical effect, I claim—

1. The combination, with the cylinder and piston of a gas and oil motor engine working with a cycle of four strokes; of an igniting-tube and an inlet-valve for the charge, a discharge-valve for the combustion-charge, a valve for the inlet of air and the escape of air and gases, and a reservoir connected with the cylinder by two passages which are governed so that in one stroke of the piston the compressed air and combustible gases previously stored in the reservoir pass therefrom into the combustible charge in the cylinder and in the other stroke of the piston the products of combustion expand from the cylinder into the reservoir, substantially as and for the purposes described.

2. In a gas or oil motor engine of the kind working with a cycle of four strokes and having a compression-space, the combination of a working-cylinder closed at both ends with a reservoir communicating with the cylinder by two passages, one situated at the extreme front end and the other at an intermediate point, so that at the suction-stroke the piston compresses air and combustion-gases into the reservoir through both passages, which air and gas are admitted into the charge through the second passage at the end of such stroke, while at the end of the working-outstroke a portion of the combustion-gases passes into the reservoir through the second passage in order to pass back into the cylinder through the said passages and during the expelling-instroke and in expanding to perform work.

3. In a four-stroke cycle gas-motor engine, wherein the cylinder is closed at the front end and communicates with a reservoir by a passage at the front end, and by a second passage at an intermediate point of its length, a valve connected to the front end of the cylinder, which valve is opened during the working-outstroke of the piston to allow of the escape of air and combustion-gases in front of the piston, and also during part of the compressing-instroke to allow of the entrance of air in front

of the piston, but is closed during the suction-outstroke and expelling-instroke, in order in the first case to allow air to be compressed in the reservoir, and in the second case to allow the combustion-gases to perform work in expanding in the front of the cylinder, substantially as herein described.

5 In testimony whereof I have signed my name

to this specification, in the presence of two subscribing witnesses, this 12th day of March, A. D. 1888.

NICOLAUS AUGUST OTTO.
